UNITED STATES PATENT OFFICE.

ABRAHAM MARTHINIUS ERICHSEN, OF PORSGRUND, NORWAY.

ELECTRIC FURNACE.

1,367,364.

Specification of Letters Patent.

Patented Feb. 1, 1921.

Application filed November 28, 1919. Serial No. 341,239.

To all whom it may concern:

Be it known that I, ABRAHAM MARTHINIUS ERICHSEN, a subject of the King of Norway, residing at Porsgrund, Norway, have invented certain new and useful Improvements in Electric Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to electrically heated furnaces, especially metal smelting furnaces, in which the principle of radiation, known from various kinds of reaction furnaces, is utilized, and in which electrical resistance bodies are arranged for that purpose above the charge of the furnace. According to the invention the resistance bars are arranged similar to grates in one or more rows above the charge and beside each other so as to be freely movable, whereby a uniform intensive heating is obtained throughout the whole extent of the charge. In order to prevent the metal vapors and other gases, that will be formed in the furnace specially upon superheating of the alloy contained in the furnace, for instance brass, from penetrating and condensing in the openings in the furnace walls, provided for the free passage of the resistance bars, whereby the free movability of the resistance bars might be prevented and their durability reduced, the space above the charge is kept under a slightly reduced pressure during the smelting process. The vapors formed will then lose their tendency of penetrating into and out from the said openings, and in fact the external air—because of the slightly reduced pressure inside the furnace—will tend to penetrate through the bar openings and into the furnace so as to keep the said openings free.

In the accompanying drawing several embodiments of the invention are shown.

Figure 1 shows the electrical smelting furnace in vertical longitudinal section.

Fig. 2 is a vertical cross section of the same.

Figs. 3-5 show three other embodiments of the furnace in section.

According to all of the embodiments shown the furnace consists of a box 2 of iron or the like, lined with refractory material 1 such as chamotte and pivoted upon trunnions 3, 4.

According to Figs. 1 and 2 the furnace rests in uprights 5, 6, and may be tilted by means of the worm wheel 7. 8 is the charging opening, which may also be used for emptying the furnace after the smelting is finished. At a distance above the bath 11 a large number of parallel electric resistance bars 10 are arranged in a row spaced a short distance apart, thus forming a flat longish resistance grate, which by its radiation effects a uniform heating of the charge to a high temperature throughout its length. The resistance bars are suspended in the furnace so as to be freely movable in the same and they penetrate out through openings 16 in the furnace wall, so that they may expand and contract according to temperature variations.

As the furnace can be tilted the charge may not only be easily emptied through the opening 8 after finishing the smelting, but during the smelting process the distance between the heating bar grate 10 and the metal bath 11 may be varied, whereby part of the molten mass may be subjected to more or less intensive heat at will (see the position indicated by dotted lines in Fig. 1).

According to Fig. 3 of the drawing a double-row grate 10 of heating bars is placed at some distance above the charge 11, said grate being in its middle interrupted by the charging hopper 13. This arrangement of the hopper permits the charge to be thoroughly preheated by the heating bar grate arranged on both sides of the hopper 13.

To prevent the metal vapors or other gases, which are formed during the smelting process, from penetrating into the openings 16 in the furnace walls, through which the resistance bars extend to the outside of the furnace, whereby the free longitudinal movement of the heating bars 10 would be interfered with, because the said vapors would condense in the openings 16, a slightly reduced pressure is maintained inside of the furnace above the charge 11. According to Fig. 3 a vent opening 14 is provided for this purpose in the furnace cover, said opening causing a gentle flow of metal vapors or

other gases out through the charging hopper 13. The openings 16 in the furnace walls thus will be kept free from the said vapors.

According to Fig. 4 a double-row resist-
5 ance grate 10 is arranged in similar manner
at a distance above the metal bath 11. The
furnace is here also provided with a special
preheating compartment 12 arranged above
the smelting compartment proper and heat-
10 ed from below by the double-row heating
bar grate 10. The vapors formed above the
smelting bath may in this construction es-
cape either through the connecting charging
hopper 17 or through lateral openings 15
15 into the preheating compartment 12 and
then through the vent opening 14 in the
cover out in the open air.

In the furnace according to Fig. 5 the
heating bars 10 are placed at right angles
20 to the tilting axis. The charging hopper 13
is disposed laterally, but in this arrangement
the preheating of the charge is not as good
as in the constructions shown in Figs. 3 and
4, in which the hoppers 13 and 17 respec-
25 tively, that lead the charge to the furnace
project through the central part of the heat-
ing grate, whereby the charge within the
hoppers is heated from both sides by the
radiation of the heating grate. The vent or
30 outflow of the escaping vapors takes place
either through the laterally provided charg-
ing hopper 13 and through the upper opening
14 or through a special vent pipe 18,
which leads to the furnace above the heating
35 bar grate. According to Fig. 5 the furnace
is placed on wheels 19 and may thus be
transported. The wheels 19 turn on the
tilting axis 4 of the furnace.

The vent openings in all of the furnace
40 constructions may preferably be adjusted, in
order to permit the control of the reduced
pressure within the furnace, and to be able
to make the vent openings very small during
particularly the latter part of the smelting
45 process. The desired adjustment of the vent
openings may be obtained in any well-
known way for instance by means of valve
slides, dampers, etc.

The resistance bars may be round, polyg-
50 onal or of any other section. Instead of be-
ing parallel, they may also be arranged like
a grate or in other ways as for instance ra-
dially or concentrically. The resistance
55 bars may also be replaced by plates arranged
beside each other.

The resistance bars consist of conductors
of second class, preferably of carbids such
as silicon carbid, and are able to endure
60 constantly temperatures of 1400-1600° cen-
tigrade. The furnace therefore is prefer-
ably employed for the smelting of metals
fusible with difficulty, the smelting points of
65 which are below the said temperatures, for
instance copper, nickel, aluminium, iron,
etc., as well as the alloys of these metals,

particularly brass alloys. The furnace,
however, may also be employed for the smelt-
ing of other materials and for other pur-
poses, for instance for distilling purposes.

Claims.

1. An electrical furnace having one or
more grate like resistors above the charge
and means to permit the furnace to be tilted
to vary the distance between the charge and
resistors.

2. Furnace according to claim 1, charac-
terized by the fact, that the furnace space
above the charge is subjected to a slightly
reduced pressure during the process in or-
der to prevent clogging by condensed va-
pors of the openings in the furnace walls,
through which the resistance bars extend to
the outside, and to thus maintain the free
movability of the resistance bars.

3. Furnace according to claim 2, charac-
terized by the fact, that above the heating
grate vent openings are provided, which
cause a slight draft (like a chimney) from
the furnace interior above the charge.

4. Furnace according to claim 3, charac-
terized by the fact, that the vent openings
are adjustable in order to control the re-
duced pressure within the furnace.

5. Furnace according to claim 1, charac-
terized by the fact, that the single-row or
double-row heating bar grate is interrupted
by the projecting charging hopper, whereby
a preheating of the charge contained in the
hopper is obtained by the heat radiation
from both sides from the heating bar grate.

6. In an electrical furnace one or more
grate like resistors arranged above the
hearth, a charging chamber arranged to ex-
tend between the resistors and below their
level but terminating above said hearth and
means for tilting said furnace to regulate
the distance of the molten bath from the
resistors.

7. In an electrical furnace, one or more
grate like resistors arranged within the fur-
nace chamber out of contact with the hearth
thereof, a charge preheating chamber ex-
tending over the resistors and having a dis-
charge hopper extending between resistors
and means to conduct gases from the furnace
110 chamber into the pre-heating chamber.

8. In an electrical furnace, one or more
grate like resistors arranged within the fur-
nace chamber out of contact with the hearth
thereof, a charge preheating chamber ex-
tending over the resistors and having dis-
charge hopper extending between resistors,
means to conduct gases from the furnace
chamber into the pre-heating chamber,
means to permit the tilting of the furnace
125 and means to draft the furnace chamber
through the pre-heating chamber, said re-
sistors resting in openings in the sides of
said furnace whereby outside air is drafted
through said openings into the furnace 130

chamber and thence into the pre-heating chamber.

9. In an electrical reverberatory furnace having a hearth, a pre-heating chamber extending over the hearth, one or more superposed rows of resistors forming grate like resistor elements arranged above the hearth beneath the pre-heating chamber, passages connecting the furnace chamber and pre-heating chamber, and a discharge hopper

extending between resistors and below their level into the furnace chamber and means to tilt the furnace.

In testimony that I claim the foregoing as my invention, I have signed my name in presence of two subscribing witnesses.

ABRAHAM MARTINUS ERICHSEN.
